COUPLER CARRIER

Edmund P. Kinne and Frank H. Kayler, Alliance,
Ohio, assignors to American Steel Foundries,
Chicago, Ill., a corporation of New Jersey

Application April 6, 1942, Serial No. 437,798

25 Claims. (Cl. 213—61)

Our invention relates to a carrier for a railway car coupler and more particularly to a carrier for a coupler of the tight lock type. Our invention comprehends such a coupler carrier which is slidably mounted on a support beam and which affords a resilient and slidable support for a tight lock car coupler.

As coupled tight lock couplers have no provision for contour angling vertically or horizontally, the coupler heads must be allowed much greater side motion with respect to the car than is allowed previous designs of couplers. This necessity for wide coupler angling necessitates an opening in the car end, the width of which depends to a considerable degree upon the type of carrier device provided for support of the coupler and arranged to slide on a support beam.

An object of our invention is to design a carrier such as above described which may be utilized with a beam of minimum length and which is afforded a long bearing base on said beam. This object is accomplished by designing a carrier comprising bifurcated end portions adapted for telescopic engagement with the upright end portions of the associated support beam.

A further object of our invention is to design a carrier such as above described in which a carrier plate is afforded a three-point spring support on an associated saddle member, said member being afforded a slidable support as above described and said carrier plate being adapted to support the shank of an associated coupler.

Another object of our invention is to provide a carrier plate having tapered bearing surfaces on the bottom thereof so that when the supported coupler is angled downward to bring the carrier plate in contact with the top of the supporting saddle member, the top portion of the plate may remain in full contact with the coupler and the under side of the plate may be provided a full bearing across the top of the saddle, thus permitting equal distribution of pressure and even stress on the supporting beam.

The A. A. R. specification for the construction of any passenger cars states in Section J that "A coupler carrier and its connections to the car structure shall be designed to resist a vertical downward thrust from the coupler shank of 100,000 pounds for any horizontal position of the coupler, without exceeding the yield points of the materials used." In view of this specification it will be readily apparent that the above described means for even loading of the beam is a very important feature of our invention.

A further object of our invention is to provide

means retaining the saddle member in engagement with the supporting beam, said means comprising guide blocks recessed in the inner surface of the front and rear walls of said member and underlying the guide flanges of said beam, said blocks being retained by means of bolt and nut assemblies received within slots in the ends of said walls.

In the drawings,

Figure 1 is a front elevation of my novel coupler carrier, the supporting beam and the supported coupler being fragmentarily shown in phantom lines, the left half of said figure showing the carrier in compressed position and the right half showing the carrier in normal position.

Figure 2 is a plan view of our novel carrier and the support beam therefor.

Figure 3 is a side elevation taken from the left as seen in Figure 1 and showing the carrier in compressed position, and Figure 4 is a side elevation taken from the right of Figure 1 and showing the carrier in normal position.

Figure 5 is a front elevation of the saddle member utilized in our novel carrier, Figures 6 and 7 being respectively a plan view thereof and an end view taken from the right as seen in Figure 5.

Figure 8 is a sectional view taken in the plane indicated by the line 8—8 of Figure 6.

Figures 9 to 13 inclusive show the carrier plate utilized in our novel coupler carrier, Figure 9 being a front elevation thereof, Figure 10 a plan view, Figure 11 a side elevation taken from the right as seen in Figure 9, and Figures 12 and 13 being sectional views taken respectively in the planes indicated by the lines 12—12 and 13—13 of Figure 10.

Figure 14 is a reduced plan view showing the application of the carrier to a coupler and particularly showing the conditions of extreme horizontal angling of said coupler.

Describing our novel coupler carrier in detail, the saddle member generally designated 2 and shown in detail in Figures 5 to 8 inclusive comprises a top wall 4 with front and rear walls 3 and 6 depending therefrom, said walls being adapted to receive therebetween an associated support beam as hereinafter more fully described. At opposite ends thereof the top wall 4 is extended upwardly as at 10 and 12, the extension 10 merging with front and rear vertical walls 16 and 14 to define therewith a bifurcated end portion or jaw 18, serving the purpose hereinafter more fully described, and the extension 12 merging with front and rear vertical walls 22 and 26

to define a bifurcated end portion or jaw 24, also serving a purpose hereinafter more fully described. The front wall 22 comprises a vertical guide surface 26 and the lug 28 vertically aligned with said surface and spaced therefrom to define a groove 30, said groove being formed and arranged for the reception of a block securing the supported carrier plate as hereinafter more fully described. The wall 22, at the outer edge thereof, comprises the lug 32 relieved as at 34 in order to lighten the saddle member. Beneath the surface 26 and in substantially vertical alignment therewith the front wall 8 is provided with a horizontal flange 36 providing a spring seat 38, said flange being reinforced by the gussets 39 and 40 and said spring seat comprising the spring positioning lug 42. At each end thereof the outer wall 8 is provided with a slot 44 and above and below said slot are lugs 46, 46 presenting arcuate faces 48, 48 adapted for engagement with a washer on an associated bolt and nut assembly, said assembly serving to retain an associated guide block as hereinafter more fully described. Beneath the spring seat 38 may be formed the depending lug 50 affording positioning means for a tie bar hereinafter more fully described. At each end and on the inner surface of the front wall 8 is formed a groove 52 for the reception of the before-mentioned guide block.

The front wall 16 comprises the guide surface 54 and a lug 56 thereabove, said wall also comprising at the outer edge thereof a lug 58 relieved as at 62 in order to lighten the saddle member. Beneath the surface 54 the front wall 8 comprises a horizontal flange 57 affording a spring seat 59, said flange 57 being reinforced by the gusset 60 and said spring seat comprising the spring positioning lug 61.

The rear wall 20 comprises the guide surface 70 and the lug 72 vertically aligned therewith and spaced therefrom to form the groove 74 formed and arranged for a purpose similar to that described for the corresponding groove 30 in the wall 22. The said rear wall 20 also comprises the lug 76 relieved as at 78 in order to lighten the saddle member, said lug 76 corresponding in form and function with the lug 32.

The rear wall 6, depending from the top wall 4, is relieved at 75 beneath the surface 70 as may best be seen in the front elevation of Figure 5 and comprises the slot 80 and the lugs 82, 82 above and below said slot, said lugs being formed and arranged similarly to the lugs 46, 46 as more clearly seen in Figure 5. The depending rear wall 6 also comprises at each end thereof and on the inner surface thereof a groove 84 formed and arranged for the reception of a guide block as hereinafter more fully described.

The rear wall 14 comprises the guide surface 86 and the lug 88 thereabove (Figure 3), and said wall 14 also comprises the lug 90 at the outer edge thereof, said lug being relieved as at 92 and affording abutment means for the associated carrier plate as hereinafter more fully described. The rear wall 6 is relieved beneath the surface 86 as at 93 and comprises therebeneath a slot 80 and lugs 82, 82 above and below said slot on the outer surface of the wall 6, said slot and said lugs corresponding with the slot 80 and the lugs 82, 82 at the opposite end of the wall 6. Intermediate its ends the wall 6 comprises a horizontal cup-like ledge 94 affording a spring seat 96 with a hollow spring positioning lug 98 thereon, the ledge 94 being reinforced by the vertical webs 100, 100. The rear wall 6 may comprise the de-

pending lug 102 reinforced by the horizontal gusset 104 and affording a support for a train line support bracket fragmentarily indicated at 106 (Figures 1, 2 and 14).

5 The carrier plate generally designated 108 shown in detail in Figures 9 to 13 inclusive, comprises a central plate portion 118 flanged at the front and rear thereof as at 120 and 122. The plate portion 118 comprises at one end thereof 10 a bifurcated portion or jaw 124 defined by the front and rear legs 126 and 128 and at the opposite end thereof the plate portion 118 comprises a bifurcated portion or jaw 130 defined by the front and rear legs 132 and 134. The rear leg 128 comprises the upstanding lug 136 adapted to about the lug 88 on the saddle member to limit upward movement of the carrier plate with respect thereto and to abut the lug 90 on the saddle member to limit transverse movement of the carrier plate with respect thereto. The front leg 126 comprises the upstanding lug 138 adapted to abut the lugs 56 and 58 on the saddle member to limit upward and transverse movement of the carrier plate with respect thereto, and the leg 126 also 20 comprises the horizontal flange 140 reinforced by the web 142, said flange 140 affording a spring seat 144 on the bottom thereof, said seat comprising the spring positioning lug 146.

The rear leg 134 on the carrier plate comprises 30 the upstanding lug 148 adapted to abut the lug 76 and the block 150 (Figures 2 and 4) positioned in the groove 74 and secured by the rivet 152, said block 150 limiting upward movement of the carrier plate with respect to the saddle member.

35 The front leg 132 comprises the upstanding lug 154 adapted to abut the lug 32 and block 156 received in the groove 30 and secured to the wall 22 on the saddle member by means of the rivet 158, said lug 154 serving a purpose similar to that 40 described for the lugs 136, 138 and 148. The front leg 132 also comprises the horizontal flange 160 affording a spring seat 162 on the bottom thereof, said seat including the spring positioning lug 164 and being reinforced by the web 166.

45 It will be apparent that the legs 126, 128, 132 and 134 guidably engage the respective guide surfaces 54, 86, 26 and 70 on the saddle member and are held in assembled relationship therewith as above described.

50 Intermediate its ends, the rear portion of the plate member 118 of the carrier plate is extended in a horizontal flange 168 and the rear depending flange 122 is continuous around the rear edge of the flange 168 to define therewith a spring seat 170 comprising the depending hollow spring positioning lug 172, and the flange 168 is reinforced by the spaced vertical webs 174, 174. Tapered bearing surfaces 176, 176, as best seen in Figures 11, 12 and 13, are provided on the bottom of the plate member 118 of the carrier plate. It may be noted that the jaw 130 at one end of the carrier plate is somewhat wider than the jaw 124 at the opposite end thereof in order that the jaw 130 may be slipped over the lugs 28 and 72 on the saddle member during assembly of the carrier.

55 The saddle member 2 and the carrier plate 108 are shown in assembled relationship and in application to a supporting beam and supported coupler shank in Figures 2 to 4 inclusive where in it may be seen that a coil spring 178 is seated at opposite ends thereof on the spring seats 59 and 144 and is positioned by the lugs 61 and 146 on said seats. A similar coil spring 180 is seated at opposite ends thereof on the spring seats 38 and 162 and is positioned by the lugs 42

and 164 on said seats and a relatively large coil spring 182 is seated at opposite ends thereof on the spring seats 96 and 170 and is positioned by the lugs 98 and 172 on said seats, said coil springs 178, 180 and 182 being precompressed and urging the carrier plate upward so that the lugs 136 and 138 on the carrier plate are in engagement with the lugs 88 and 56 on the saddle member and said springs are also operative to urge the lugs 148 and 154 on the carrier plate into engagement with the blocks 150 and 156 secured to the saddle member as heretofore described. Thus it will be seen that our invention comprehends an arrangement wherein the carrier plate is afforded a three-point spring support from the saddle member, whereby said carrier plate is enabled to follow all angular and torsional movements of the supported coupler, said three-point support comprising the front coil springs 178 and 180 and the relatively large coil spring 182, said springs being supported from respective spring seats on the saddle member at the lower ends thereof and being engaged at the upper ends thereof with respect of spring positioning means on the carrier plate. The bottom surface of the top wall 4 of the saddle member is seated as at 184 on the top of the support beam 186 as best seen in Figures 3 and 4. It may be noted that the beam 186 is of I-section and comprises the vertical web 188 and the top and bottom horizontal webs 190 and 192, said top web 190 being flanged at opposite sides thereof as at 194, 194 (Figures 2, 3 and 14). The saddle member is retained in engagement with said beam by means of guide blocks 196, 196 positioned in the grooves 52, 52 and retained by bolt and nut assemblies 198, 198, said assemblies being slipped into the slots 44, 44 and retained therein by engagement of the washers 200, 200 with the arcuate surfaces 48, 48 on the lugs 46, 46 positioned above and below the slots 44, 44 as may be clearly seen in Figure 1. The saddle member is also retained with respect to the beam 186 by guide blocks 202, 202 similar to the blocks 196, 196 and positioned in the recesses 84, 84, said blocks being retained by the bolt and nut assemblies 204, 204 received in the slots 80, 80 and retained therein by the washers 206, 206 engaged with the arcuate surfaces on the lugs 82, 82 in a manner similar to the engagement of the washers 200, 200 with the arcuate surfaces on the lugs 46, 46. Further securing means is afforded by the L-shaped tie bar 208 secured as at 210, 210 to the depending lugs 50 and 102 on the saddle member 2, said tie bar underlying the beam 186 as may be clearly seen in Figures 1, 3 and 4. A coupler shank 212 is seated as at 214 on the top of the plate portion 118 of the carrier plate 108.

Figure 3 and the left half of Figure 1 show the coupler shank 212 in a position of extreme vertical angling in which the carrier plate is urged downwardly so that the tapered bearing surfaces 176, 176 abut the top wall 4 of the saddle member 2. It will be apparent that by means of the tapered surfaces 176, 176 pressure will be evenly transmitted to the beam 186 during extreme vertical angling of the coupler.

Figure 14 shows a plan view of my novel coupler carrier with a coupler applied thereto, said coupler having a head generally designated 216 and the before-mentioned shank 212 adapted to be pivotally connected as at 218 to a yoke member (not shown), and in this figure it may be clearly seen that the beam 186 comprises upstanding end portions 220, 220 shown in sectional

view. At the top of Figure 14 is shown in phantom lines the position assumed by my novel coupler carrier during extreme horizontal angling of the supported coupler and it may be seen that the shank 212 of the coupler abuts the wall 12 of the saddle member so that said member slides along the beam 186 as the coupler angles horizontally and that the jaw 24 of the saddle member receives therewithin the associated upstanding end portion 220 of the beam 186 so that the upstanding wall 12 of the saddle member abuts said end portion as at 222 in order to limit horizontal angling of the coupler. It will be readily understood that the jaw 18 of the saddle member is similarly adapted to engage the associated end portion 220 of the beam 186 in the event that the coupler angles in the opposite direction from the position indicated in phantom lines at the top of Figure 14. Also, it may be noted that brackets 224, 224 are secured to the ends of the beam 186, 186 and furnish support for an operating rod 226 secured as at 228 to said brackets, said bar underlying the shank 212 of the coupler.

It is to be understood that we do not wish to be limited by the exact embodiment of the device shown which is merely by way of illustration and not limitation as various and other forms of the device will, of course, be apparent to those skilled in the art without departing from the spirit of the invention or the scope of the claims.

We claim:

1. In a coupler mounting, a support beam with upstanding ends, a saddle member comprising a top wall seated on said beam and depending walls at opposite sides thereof, bifurcated upstanding end portions on said member, each of said end portions comprising front and rear walls defining a jaw adapted to receive therewithin the associated end of said beam, spring seats on said member at opposite sides thereof, coil springs seated thereon, a carrier plate supported on said springs and comprising bifurcated end portions receiving respective end portions of said saddle member, and a coupler comprising a shank seated upon said plate and adapted to abut the upstanding end portions of said saddle member.

2. In a coupler mounting, a supporting beam with upstanding ends, a saddle member slidably seated on said beam and having end portions adapted to telescopically engage the ends of said beam, resilient means on said saddle member at opposite sides thereof, a carrier plate mounted on said means and interlocked with said saddle member, a coupler comprising a shank seated on said carrier plate, means on said saddle member adapted to engage said shank whereby said member is moved along said beam during horizontal angling of said coupler, depending lugs on said saddle member at opposite sides of said beam, and a tie bar connected between said lugs and underlying said beam.

3. In a coupler support means, the combination of a beam, a carrier member having a web slidably seated on said beam along substantially flat surfaces on said beam and said web, said member comprising spring seats at opposite sides of said web, springs on said seats, a carrier plate having spring seats at opposite sides thereof engaging the upper ends of said springs, said plate comprising a web normally spaced above the first-mentioned web and adapted for abutment therewith under certain conditions to limit com-

pression of said springs, one of said webs being tapered in thickness transversely thereof and the other of said webs being of substantially uniform thickness to afford full flat face bearing between the adjacent surfaces of said webs upon extreme downward and tilting movement of the carrier plate.

4. In a coupler carrier, a member having a wall with a bottom surface for slidable bearing against an associated support element, said wall having a top abutment surface extending from side to side thereof, spring seats on said member disposed at opposite sides of said wall beneath the plane thereof, springs on said seats, a carrier plate supported by said springs, and an abutment surface on the bottom of said carrier plate extending transversely thereof and formed and arranged for engagement with said first-mentioned abutment surface during extreme downward movement of said plate.

5. In a coupler support, a beam with upstanding end portions, a saddle member slidably supported on said beam and having end portions adapted to telescopically engage said first-mentioned end portions, coil springs mounted on said saddle member at opposite sides thereof, a carrier plate seated on said springs and interlocked with said saddle member, a coupler comprising a shank seated on said carrier plate, and means on said saddle member adapted to engage said shank, whereby said member is moved along said beam during horizontal angling of said coupler.

6. In a coupler carrier, a member adapted for engagement with associated support means, said member comprising a top bearing surface, a carrier member resiliently supported from the first-mentioned member and having a bottom surface adapted for abutment under certain operating conditions with said bearing surface, said carrier member having a normally substantially horizontal top seat for an associated coupler, one of said surfaces being inclined transversely of said carrier and the other of said surfaces being approximately horizontal to accommodate bearing throughout said surfaces under certain operating conditions.

7. In an element of a coupler carrier, a member having a web affording a substantially flat bearing surface for an associated carrier plate, and three substantially horizontal spring seats on said member at opposite sides of said web, one of said seats being disposed at one side of said web approximately midway intermediate the ends thereof and the other of said seats being disposed at the opposite side of said web adjacent opposite ends thereof.

8. In an element of a coupler carrier, a member having upstanding end portions adapted to embrace an associated coupler shank, seating means on said member for associated resilient means, and stop means on opposite sides of each end portion adjacent its upper extremity for limiting relative upward movement of an associated carrier plate, the stop means on at least one of said end portions being removable.

9. In an element of a coupler carrier, a member having upstanding end portions adapted to embrace an associated coupler shank, seating means on said member for associated resilient means, and stop lugs at opposite sides of each end portion for limiting relative longitudinal movement of an associated carrier plate with respect to said element.

10. An element of a coupler carrier, comprising a web with substantially flat top and bottom bearing surfaces and spring seats at opposite sides of said web, said web being tapered in thickness toward one of said sides thereof.

11. In a carrier plate for a coupler carrier, a member having a web presenting substantially flat bearing surfaces on the top and bottom thereof, and substantially horizontal spring seats on said member at opposite sides of said web, said web tapering in thickness toward one of said sides of said web.

12. In a coupler carrier, a saddle member comprising upstanding bifurcated end portions formed and arranged for telescopic engagement with the ends of an associated support beam, and a carrier plate resiliently mounted on said saddle member and having bifurcated end portions receiving therewithin the first-mentioned end portions for interlocking engagement therewith.

13. In a carrier plate for a coupler carrier, a member having bifurcated end portions each comprising spaced legs, and spring seats at opposite sides of said member on the bottom thereof, certain of said seats being formed on the legs of said bifurcated portions at one side of said member.

14. In a carrier plate for a coupler carrier, a member having bifurcated end portions each comprising spaced legs, and spring seats at opposite sides of said member on the bottom thereof, certain of said seats being formed on the legs of said bifurcated portions at one side of said member, and another of said seats being formed on the opposite side of said member intermediate said bifurcated portions.

15. In a carrier plate for a coupler carrier, a member having bifurcated end portions each comprising spaced legs adapted to embrace an associated portion of a supporting element, a substantially flat bearing surface on the bottom of said member for abutment with said element, and spring seats at opposite sides of said member on the bottom thereof and beneath the level of said surface.

16. In a carrier plate for a coupler carrier, a member having bifurcated end portions each comprising spaced legs adapted to embrace an associated portion of a supporting element, a substantially flat bearing surface on the bottom of said member for abutment with said element, spring seats at opposite sides of said member, and a stop lug atop each leg presenting a substantially flat surface adapted for abutment with means on the associated portion of said element to limit upward movement of said member with respect thereto.

17. In a carrier plate for a coupler carrier, a member having bifurcated end portions each comprising spaced legs adapted to embrace an associated end portion of a supporting element, a substantially flat bearing surface on the bottom of said member for abutment with said element, substantially horizontal spring seats on said member at opposite sides thereof beneath the level of said surface, and stop means on each leg adjacent the outer extremity thereof to limit relative longitudinal movement of said member with respect to said element.

18. In a carrier plate for a coupler carrier, a member having bifurcated end portions each comprising spaced legs adapted to embrace an associated end portion of a supporting element, said member comprising a central web having substantially flat bearing surfaces on the top and

bottom of said surface.

19. In a carrier plate for a coupler carrier, a member having bifurcated end portions each comprising spaced legs adapted to embrace an associated portion of a supporting element, a substantially flat bearing surface on the bottom of said member for abutment with said element, substantially horizontal spring seats on said member at opposite sides thereof beneath the level of said surface, and stop means on each leg adjacent the outer extremity thereof to limit relative longitudinal movement of said member with respect to said element.

20. In a carrier plate for a coupler carrier, a member having bifurcated end portions each comprising spaced legs adapted to embrace an associated portion of a supporting element, a substantially flat bearing surface on the bottom of said member for abutment with said element, substantially horizontal spring seats on said member at opposite sides thereof beneath the level of said surface, and stop means on each leg adjacent the outer extremity thereof to limit relative longitudinal movement of said member with respect to said element.

21. In a carrier plate for a coupler carrier, a member having bifurcated end portions each comprising spaced legs adapted to embrace an associated portion of a supporting element, a substantially flat bearing surface on the bottom of said member for abutment with said element, substantially horizontal spring seats on said member at opposite sides thereof beneath the level of said surface, and stop means on each leg adjacent the outer extremity thereof to limit relative longitudinal movement of said member with respect to said element.

22. In a carrier plate for a coupler carrier, a member having bifurcated end portions each comprising spaced legs adapted to embrace an associated portion of a supporting element, said member comprising a central web having substantially flat bearing surfaces on the top and

bottom of said surface.

bottom thereof, and spring seats at opposite sides of said member, said web tapering in thickness toward one of said sides.

19. In a coupler carrier, a saddle member having a top wall adapted for seating on an associated support beam, spaced walls depending from opposite sides of said top wall, upstanding end portions on said member, resilient means supported on said member, and a carrier plate supported on said resilient means and comprising bifurcated end portions receiving respective of said first-mentioned end portions.

20. In a coupler carrier, a saddle member comprising a wall having a bottom surface for slid- able engagement with an associated support beam, said saddle member comprising bifurcated end portions upstanding from said wall and formed and arranged for telescopic engagement with the ends of said beam, a spring seat on said saddle member intermediate the ends thereof and disposed at one side of said wall, a pair of spring seats on said saddle member adjacent opposite ends thereof and disposed at the other side of said wall, springs on said seats, and a carrier plate supported from said springs and having bifurcated end portions receiving therewithin first-mentioned end portions for interlocking en- gagement therewith.

21. In a coupler support, a beam, a saddle member slidingly supported on said beam, coil springs mounted on said saddle member at opposite sides thereof, a carrier plate seated on said springs and interlocked with said saddle member, and a coupler comprising a shank seated on said carrier plate.

22. In a coupler carrier, a saddle member comprising a top wall and spaced walls depending therefrom at opposite sides thereof, spring seats formed on the outer sides of said depending walls below the level of said top wall, upstanding por- tions at opposite ends of said member for em-

bracing an associated coupler shank, springs on said seats, and a carrier plate member supported on said springs and affording a seat for said shank.

5 23. In a coupler carrier, a saddle member comprising a top wall and spaced walls depending therefrom at opposite sides thereof, spring seats formed on the remote surfaces of said depend- ing walls below said top wall, upstanding portions 10 at opposite ends of said member for embracing an associated coupler shank, springs on said seats, and a carrier plate member supported on said springs and affording a seat for said shank, said plate member having bifurcated end por- tions for reception of respective of the first-men- tioned portions.

20 24. In a coupler carrier, a saddle member comprising a top wall and spaced walls depending therefrom at opposite sides thereof, spring seats formed on the exterior surfaces of said depend- ing walls below the level of said top wall, up- standing portions at opposite ends of said mem- ber for embracing an associated coupler shank, springs on said seats, and a carrier plate mem- 25 ber supported on said springs and affording a seat for said shank, said plate member being inter- locked with said portions.

25 25. In a coupler carrier, a saddle member comprising a top wall and spaced walls depending therefrom at opposite sides thereof, spring seats formed on the outer sides of said depending walls beneath the plane of said top wall, upstanding portions at opposite ends of said member for embrac- 30 ing an associated coupler shank, springs on said seats, and a carrier plate member sup- 35 ported on said springs and affording a seat for said shank, said top wall and said plate member having cooperative bearing surfaces adapted for abutment under certain operating conditions.

40 EDMUND P. KINNE.
FRANK H. KAYLER.
